(57) **CLAIM**

The ornamental design for a battery package, as shown and described.

DESCRIPTION

FIG. 1 is a perspective view of a battery package in a closed position, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the battery package in a partially open position; and,

FIG. 9 is a perspective view of the battery package in an open position.

The broken lines are for illustrative purpose only and forms no part of the claimed design.
